(57) CLAIM

The ornamental design for a dish cleaning tool head, as shown and described.

DESCRIPTION

FIG. 1 is a perspective view of a dish cleaning tool head showing my new design, the dish cleaning tool head provided as part of a bristle tool head;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a perspective view of the dish cleaning tool head provided as part of a sponge head;

FIG. 9 is a front elevation view of FIG. 8;

FIG. 10 is a rear elevation view of FIG. 8;

FIG. 11 is a left side elevation view of FIG. 8;

FIG. 12 is a right side elevation view of FIG. 8;

FIG. 13 is a top plan view of FIG. 8; and,

FIG. 14 is a bottom plan view of FIG. 8.

The dash-dash broken lines shown in the figures represent portions of the dish cleaning tool head that form no part of the claimed design. The dash-dot broken lines shown in the figures represent boundaries of the claim that form no part of the claimed design.

1 Claim, 8 Drawing Sheets
